DUOPNEUMATIC HANDLE FOR AIR-METHOD
CLEANERS

Daniel Benson Repleglo, Berkeley, Calif., assignor
to The Ohio Citizens Trust Company, Toledo,
Ohio, a corporation of Ohio, as trustee

Application August 11, 1936, Serial No. 95,414

8 Claims. (Cl. 15—9)

The invention relates to cleaning apparatus and more particularly to portable electric cleaners of the air-method type, which may be selectively employed for floor cleaning purposes or by the 5 use of suitable extension devices may be employed for cleaning walls, furniture, draperies and the like.

One of the objects of the invention is to provide improved means for controlling the flow of 10 dust laden air into the air filtering and dust collecting device with which the apparatus is equipped, from the floor tool or from the extension devices as the case may be.

Another object is to provide a light weight 15 cleaner, preferably utilizing modern materials such as the recently developed synthetic resins and other plastics, so that the entire apparatus may be readily lifted by the operator.

A further object of the invention is to provide 20 an apparatus which includes an elongated suction pipe communicating intermediate its ends with the dust separating means and the source of suction, said device being provided with valve means whereby either end of the pipe may be 25 placed in communication with said dust collector and source of suction while the other end is cut off, from the source of suction.

A further object of the invention is to provide 30 a cleaner in which the various elements of the "air-way" cleaning system may be utilized.

The invention will be more readily understood by reference to the accompanying drawings and the following detailed description. These are furnished by way of illustration rather than by way of limitation.

In the drawings:

Fig. 1 is a side elevation of the improved cleaner embodying the invention, portions being broken away to show the interior.

Fig. 2 is an enlarged detailed view partly in side elevation and partly in section showing the air-flow control valve in the floor cleaning position.

Fig. 3 is a side elevation showing the control valve in position to permit air to be drawn through that end of the suction handle remote from the floor tool.

Fig. 4 is an exploded view showing in perspective the various parts of the air-flow control valve.

Fig. 5 is a section on the line 5—5 of Fig. 2.

Fig. 6 is a side elevation showing the dust collecting means partially withdrawn from its housing.

Fig. 7 is a side elevation showing the cleaner in repose position.

Fig. 8 is a rear view showing the apparatus functioning as a blower, and

Fig. 9 is a side elevation showing the cleaner 5 reversed and the usual handle grip end serving as a floor tool.

Referring to the drawings in detail the reference numeral 10 denotes a cylindrical housing or caddy which is preferably made of light weight 10 non-conducting material such as Bakelite or hard fiber. Metal may be employed although non-conductors are preferred.

The reference numeral 11 denotes a power plant of multiple type such as is disclosed in my 15 pending application Serial No. 64,420 filed February 17, 1936, showing a plurality of motor and fan units preferably operating in opposite directions. The said application may be referred to for details of construction. The lower end of 20 the caddy is closed by a removable cap 12 preferably provided with a pair of lateral outlets 13, either of which may be capped. Each opening is preferably of sufficient size to take the entire output from the power plant. The device may 25 be arranged to function as a blower as indicated in Fig. 8 in which case an extension device 58 may be attached to one of the outlets while the other is closed by a cap 51.

A hinged collapsible support 14 having rollers 30 is preferably provided at a location just above the power plant, this support or bracket being adapted to be opened up as indicated in Fig. 1 wherein the bracket together with the floor tool of the cleaner supports the caddy and associated mechanism in inclined position. The bracket may however be folded against the body of the cleaner so as to be out of the way as indicated in Figs. 7 and 9.

Current may be supplied to the power plant through the cord 15, part of which may be carried by the caddy while another portion is separable therefrom and is adapted to be plugged into the portion which is carried by the caddy and at the other end to be plugged into a wall 45 socket or the like. Owing to the insulating quality of the caddy wall there is no danger of short circuiting.

The upper portion of the caddy is occupied by the dust collecting and air filtering apparatus. 50 As shown such apparatus includes a removable inner porous paper bag 16 which may be removed when filled and replaced with another bag, the step of removal being indicated in Fig. 6. An outer close mesh fabric bag 17 composed of

cloth, wire netting or other suitable material may be secured within the caddy and serves as an outer support to prevent bursting of the paper bag and to keep the same from contact with the outer walls of the caddy.

The mouth 18 of the paper bag is shown as connected by means of a flexible band of rubber or the like 19 to the reduced neck of a cap 20 which is provided with a flange 21 fitting within 10 the top of the caddy. This cap is provided with a transparent top 22 which permits the operator to see the amount of dust which is being drawn into the air filtering bag. According to my invention, dust laden air may be drawn into the 15 cap from either of two sources, one of which may be a floor tool located at one end of a tubular suction pipe and the other is located at the opposite end of the suction pipe.

A suitable valve is located intermediate the 20 ends of the suction pipe and is controlled by the angular position of the handle grip. According to the herein described embodiment of the invention the movable portion of the valve is carried by the handle grip while the fixed portion 25 is associated with the transparent cap.

The fixed member associated with the caddy cap is substantially Y-shaped in form and includes a short pipe section 24 communicating with an opening 25 in the top of the cap. This 30 pipe section is preferably permanently secured to the cap and may be of metal, fiber or other material which may be molded, cast or shaped. A valve casing member 26 is secured at the top of the pipe section 24 and is open at the top to receive the movable portion of the valve. The valve casing is in communication with a short pipe section 27 which extends outwardly and communicates with another short member 28 extending downwardly and adapted to fit in 40 a collar 29 which is connected to the top of the caddy. A long pipe section 30, which may be composed of hard fiber, Bakelite, metal or other suitable material, fits into the lower portion of the collar 29 at one end and at the other end 45 fits into a socket 31 integral with the lower cap 12. The pipe 30 is shown as curved so that its ends are at opposite sides of the central axis of the caddy. Another pipe section 32 may be attached to the lower side of the socket 31 and 50 is connected to a floor tool 33 the connection including an inclined rotatable joint 34 as disclosed in my Patent No. 1,994,868 dated March 19, 1935.

To return to the description of the valve mechanism and with particular reference to Fig. 4 it will be noted that the suction handle grip portion 35 is provided with a swinging valve member 36 which is adapted to be hingedly secured within the valve casing member 26 by 60 means of a bolt 37 which may be provided with conical spring washers at either end so that an air-tight fit may be secured. The valve member 36 is provided with two passages one indicated at 38 being adapted to place the handle grip in communication with the air filtering means through the pipe section 24, while the other 39 is adapted to place the pipe 30 leading from the floor tool in communication with the air filtering means. It will be obvious that when one of the suction passages is operative the other is 70 automatically rendered inoperative and the functioning of the valve is determined by the angular position of the handle grip 35.

In Fig. 2 the valve is shown in position to place 75 the floor tool in operative position while in Fig.

3 the floor tool is rendered inoperative whereas the extension tube on the handle grip portion communicates with the source of suction.

The cap 20 and associated mechanism is adapted to be held in position by means of a bail 5 40 secured to a strap at the top of the caddy and fitting behind a detent 41 on the stub pipe section 27.

When the bail 40 is lowered as indicated in Fig. 6 the cap together with the inner dust collecting bag and also the valve mechanism associated with the cap may be withdrawn from the caddy to permit replacement of the bag.

A tension spring 42 tends to hold the handle grip and associated valve mechanism in the 15 position shown in Fig. 2 so as to render the floor cleaning apparatus operative but the valve may be locked in the other position by any suitable means as for example a U-shaped latch 43, the legs of which fit into bosses 44 while the 20 loop of the U-shaped member engages a notch 45 thereby tending to hold the valve against the tension of the spring 42.

Operation

For ordinary floor cleaning purposes the apparatus assumes the position shown in Fig. 1 with the handle grip portion in the lowered position. The bracket or support 14 is opened up and it, together with the rollers on the ends 30 of the floor tool, serves to support the cleaner in the inclined position shown. The cleaner may be moved to and fro over the floor in the usual manner. The handle grip having been placed in the proper position current is turned 35 on and the fan motor started thus creating suction which draws dust laden air into the filter where the dust is separated from the air and the filtered air discharged through one or both of the outlets 13 or through a suitable blower 40 pipe 50 or other suitable extension devices where blowing action is desired as indicated in Fig. 8. A suitable length of flexible hose may be employed to reach any desired position and any desired type of extension devices or extension 45 tools may be used.

When the cleaner bag has become fouled by continued use, the bail 40 is lowered permitting the cap 20 with the inner bag 16 attached thereto to be withdrawn by means of the grip member 35 serving as a handle. The old bag may then be removed and replaced by a new one. The bag and cap are then assembled with the caddy and held in place by the bail 40.

When it is desired to draw air through the 55 handle grip portion 35 the same is raised against the tension of the spring and may be held in place by the U-shaped latch member or other suitable mechanism.

The hose extension members may be attached 60 to the handle grip and used for cleaning walls, ceilings, furniture, draperies and the like. Such extension members are disclosed for example in my Patent No. 1,533,271 dated April 14, 1925.

The open end of the handle grip 35 may be 65 supported by a bracket 46 which may be of the flexible type shown in my Patent No. 1,884,870 dated Oct. 25, 1932. This bracket may be provided with a hollow connector member 47 such as shown in the aforesaid patent to which is attached an extension hose 48 provided with a dusting tool on one end which may be of the type shown in my Patent No. 1,994,871 dated March 19, 1935. Obviously any type of extension members may be utilized.

When the cleaner is in the closeted position shown in Fig. 7 it performs substantially the function of the usual stationary suction cleaning apparatus but may be readily released to function for ordinary floor cleaning purposes. If desired the floor tool may be supported as in my Patent No. 1,884,868 dated October 25, 1932 to prevent the same from sliding away from the wall or the body of the cleaner may be supported in any suitable manner. It will be observed that the tension of the spring bracket 46 is directed in such a manner as to tend to overcome the tension of the spring 42 and thus the bracket 46 is possessed of greater strength than the spring 42 may serve to hold the valve open so as to connect with the extension devices and to disconnect the floor tool without requiring the assistance of the U-shaped latch member 43.

Owing to the lightness of the cleaner as a whole, due to the light weight materials employed, the body of the cleaner may be lifted by the operator and the apparatus used in the inverted position shown in Fig. 9. In this case the extension pipe 32 and the floor tool 33 may be held in the hand of the operator. The pipe section 35 in such case serves as a floor tool. If desired the usual floor tool 33 may be removed from the pipe 32 and attached to the member 35, the floor tool being removable as disclosed in my Patent No. 1,994,868, and the diameter of the pipe 35 being the same as that of the pipe 32.

It will be observed that the weight of the cleaner tends to hold the valve against the tension of the spring 42 so that where the member 35 is used as a floor tool with the apparatus in the inverted position the holding latch 43 again becomes non-essential. However it may be desirable to use this member to prevent the pipe 35 from folding over whenever downward pressure is released as when the cleaner is lifted entirely from the floor.

The invention has been described in detail for the purpose of illustration but it will be obvious that many variations and modifications may be resorted to within the scope of the invention.

I claim:

1. A suction cleaner comprising a suction pipe handle adapted to connect with suction cleaning tools at either end, suction producing and dust collecting means operatively connected to the handle intermediate its ends, said handle including a relatively fixed pipe section and a movable handle grip portion hingedly connected to the fixed section, and valve means actuated by said movable portion serving to selectively place one end of the handle in communication with the suction producing means, while cutting off communication with the other end, the movable section being mounted to swing about a pivot at right angles to the axis of the fixed pipe section.

2. A suction cleaner comprising a cylindrical container having an inlet opening at one end and a discharge opening at the other, and housing suction producing means at the discharge end and dust collecting and air filtering means at the other, a cap for said container having an inlet through which dust laden air may be drawn by said suction producing means, and valve means controlling said inlet and adapted to connect the same with one or another of a pair of airways, leading from different cleaning tools, one of said airways being relatively fixed and the other comprising a pivoted handle grip member connected with the movable portion of the valve, said handle grip being adapted to swing about a pivot at

right angles to the central axis of the fixed member.

3. A suction cleaner comprising a cylindrical container having an inlet opening at one end and a discharge opening at the other, and housing suction producing means at one end and dust collecting and air filtering means at the other, a cap for said container having an inlet through which dust laden air may be drawn by said suction producing means, valve means controlling said inlet and adapted to connect the same with one or another of a pair of airways, leading from different cleaning tools, one of said airways comprising a pivoted handle grip member connected with the movable portion of the valve, and the other being relatively fixed, and means for retaining the handle grip portion in one or another of two angular positions, to regulate the direction of air flow, said handle grip being adapted to swing about a pivot at right angles to the central axis of the fixed member.

4. In a suction cleaner, a suction producing and air filtering means, a floor tool, a hinged suction pipe having a valve means associated therewith adapted to connect the floor tool to said suction producing and air filtering means when downward pressure is applied to the floor tool, resilient means tending to move the valve to cut off communication through said hinged pipe when the tool is lifted from the floor, and means whereby the hinged pipe may be retained in open position.

5. In a suction cleaner, a source of suction, an open ended suction pipe communicating intermediate its ends with the source of suction and adapted to be connected at either end with suction tools, said pipe including a relatively fixed pipe section and a movable pipe section hingedly connected to the fixed section, and valve means actuated by the movable section for controlling the flow of air through said suction pipe, the movable section being mounted to swing about a pivot at right angles to the axis of the fixed pipe section.

6. In a portable suction cleaner, a source of suction, an open ended suction pipe communicating intermediate its ends with the source of suction, and adapted to be connected at either end with suction tools, said pipe including a relatively fixed pipe section and a movable section hingedly connected to the fixed section and adapted to serve as a handle grip for moving the cleaner across the floor, valve means actuated by angular movement of said handle grip for controlling flow of air through said suction pipe, resilient means urging the handle grip to one angular position, and means for latching the handle grip in another angular position.

7. A suction cleaner comprising a tubular conduit having an air inlet and a discharge outlet, air filtering means within said conduit, a suction pipe communicating intermediate its ends with the inlet end of said conduit, and adapted to be connected at either end with suction tools, said pipe including a relatively fixed pipe section and a movable section hingedly connected to the fixed section, and valve means, actuated by swinging said movable section about its hinge to one of two angular positions, for directing the flow of dust laden air to said filter from one end or the other of said suction pipe, the movable section being mounted to swing about a pivot at right angles to the axis of the fixed pipe section.

8. A suction cleaner comprising a tubular container having an inlet at one end and an outlet

at the other and housing air filtering means adjacent the inlet end, communicating with a source of suction, a tubular member extending lengthwise of the container and fixed thereto, and a
5 detachable tubular fitting including three interconnected pipe sections, one of which is provided with a cap adapted to fit the inlet end of said container, another of which is adapted to fit the top of said fixed tubular member, while the third
10 pipe section is movable with reference to the

other two and is mounted to swing about a pivot at right angles to the common plane which includes the central axes of the other two, and a valve at the juncture of the said pipe sections adapted to be actuated by said movable section, 5 and serving to selectively place said fixed tubular member and said movable pipe section in communication with the source of suction.

DANIEL BENSON REPLOGLE. 10
